WATCHCASE TOOL

William S. Chase and Anthony F. Polance, Flint, Mich.

Application May 25, 1954, Serial No. 432,138

1 Claim. (Cl. 81—6)

The present invention relates to new and useful improvements in watchcase tools for use in removing the backs of waterproof watches which are threaded onto the case and for other purposes where a tool having adjustable jaws is useful.

An important object of the invention is to provide a tool having a fixed jaw and a slidable jaw secured in an adjusted position relative to the fixed jaw and forming each jaw with parallel spanner wrench extensions adapted for engaging notches or recesses in the back of a watchcase to facilitate removal thereof.

Another object is to provide a tool of this character of simple and practical construction, which is efficient and reliable in operation, relatively inexpensive to manufacture and otherwise well adapted for the purpose for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view;

Figure 2 is an enlarged fragmentary longitudinal sectional view taken on a line 2—2 of Figure 1; and

Figure 3 is an enlarged transverse sectional view taken on a line 3—3 of Figure 1.

Referring now to the drawing in detail, wherein for the purpose of illustration, we have disclosed a preferred embodiment of our invention, the numeral 5 designates a T-shaped handle including a flat bar or shank 6 of strap metal or other suitable material and having its front end secured in a recess 7 in the top of a transverse stationary gripping jaw 8 which has its end portions 9 and 10 projecting outwardly at the opposite side edges of the bar.

The bar 6 is formed with a longitudinal slot 11 adjacent the stationary jaw 8 and in which a threaded stud 12 is slidable. The lower end of the stud is threaded or otherwise fixed in a movable gripping jaw 13 which extends transversely of bar 6 and parallel to jaw 8 and a nut 14 is threaded on the upper end of the stud and is tightened against the top of the bar by a handle 15 extending trans-

2

versely through the upper portion of the nut. Jaw 13 is also formed at its upper surface with a recess 16 to receive the bar 6 to prevent turning of the jaw relative to the bar.

5 The end portions 17 and 18 of jaw 13 also project outwardly at the opposite side edges of the bar 6 and the adjacent ends 10 and 18 of jaws 8 and 13 are formed with tapered square-shaped extensions or spanner wrench jaws 19 and 20.

10 In the operation of the tool, the rear end of bar 6 forms a handle 21 and jaw 13 is adjusted to fit the spanner wrench jaws 19 and 20 in the recesses or notches usually formed in the threaded type back of a watchcase (not shown) to facilitate unscrewing and removal of the back.

15 The opposing jaw faces 22 and 23 of jaws 8 and 13 may also be used for gripping nuts or other work in the manner of an adjustable wrench.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

What is claimed as new is as follows:

A watchcase tool comprising: a flat bar having a longitudinal slot in one end portion, a transversely elongated stationary gripping jaw secured on one side of said one end portion of said bar and projecting laterally beyond the longitudinal edges thereof, a transversely elongated movable gripping jaw mounted for longitudinal adjustment on said one side of the bar and projecting laterally beyond the longitudinal edges thereof, said movable jaw traversing the slot and being opposed to and cooperable with said stationary jaw, a stud threadedly mounted in the movable jaw and operable in the slot, a nut comprising an operating handle, threaded on said stud and engageable with the bar for frictionally securing the movable jaw in adjusted position, and parallel spanner jaws integral with one end of the gripping jaws and extending therefrom at right angles to the bar, said gripping jaws having recesses therein accommodating the bar for positively retaining said gripping jaws against turning thereon.
